N. BRAYER.

HEATING STOVE.

No. 15,184.

Patented Aug. 5, 1884.

UNITED STATES PATENT OFFICE.

NICHOLAS BRAYER, OF ROCHESTER, NEW YORK, ASSIGNOR TO THE
CO OPERATIVE FOUNDRY COMPANY, OF SAME PLACE.

DESIGN FOR A HEATING-STOVE.

SPECIFICATION forming part of Design No. 15,184, dated August 5, 1884.

Application filed June 16, 1884. Term of patent 3½ years.

To all whom it may concern:

Be it known that I, NICHOLAS BRAYER, of Rochester, in the county of Monroe and State of New York, have invented a Design for 5 Heating-Stoves, of which the following is a specification.

My design relates to that particular type of stoves commonly known in the art as "magazine" stoves, which possess certain distinctive 15 characteristics in form and appearance.

My design embraces a body of octagonal form in cross-section, or, in other words, of the form of an elongated rectangle, having the corners chamfered or beveled in a vertical direction. There are several sections one above 20 another, decreasing in size successively.

Referring to the details of the design, A represents a base portion provided with legs at the corners. Horizontally it is of substantially rectangular form, the corners being beveled or cut away. The outer faces of the leg portions *a* bear in relief ornaments in form of a Maltese cross, together with minor ornamental lines, such as shown. The intermediate vertical portions between the legs bear rosettes *c* and ornamental figures *d*.

Above the base A there is what is known as a "bottom plate," B, forming the base of the body portion proper. It is essentially the 30 same outline horizontally as the leg portion, and is beaded or molded on the outer edge, as shown. On the front, and on each of the two ends, it bears a panel, *e*, having in relief thereon ornamental rosettes and other ornamental figures, such as represented. At each of the 35 four corners the portion C bears smaller panels *f*, having in relief ornamental figures corresponding in style with those on the panels *e*.

At each end ornamental brackets *g* rise from 40 the ash-pit section C, supporting at their upper ends a horizontal bar, *h*, the ends of which are fashioned into ornamental knobs. At the top of the ash-pit section there is a horizontal top plate D projecting outward beyond the 45 lower section and extending downward at the outer edge. At the front of this plate D, provided with an ornamental plate, is the rail E, following its edge, as represented.

Above the plate D there rises the main or 50 body portion, consisting of a grate-section, F,

and the fire-pot section G. These sections have essentially the same outline or marginal form as the sections below. The ash-pit section has at the front and at the two ends ornamental door-frames H, of an open or skeleton form, to receive transparent lights or panes. The grate section F has ornamental panels I at the corners. The fire-pot section G has at the front and end doors K, similar in form and appearance to those of the grate-section. It also has 60 at each of the four corners a skeleton door, L, to receive a transparent pane. These doors L are of a form or configuration corresponding with that of the other doors before mentioned. These doors applied to the four corners of the 65 fire-pot section constitute a marked feature of my design.

Above the doors of the fire-pot, on the front and side faces, and on each of the four corners, are formed panels M, encircled by an ornamental beading or molding, and bearing in relief ornamental designs composed of vines and flowers entwined in the manner represented. Above these panels, and overhanging the faces 70 of the body portion, is an ornamental plate, N, 75 arched or curved upward at the middle on the front and rear sides. The edges of this plate are turned downward to present faces which are made of a flat form and commonly burnished and plated. At the front an ornamental plate, N', is placed beneath the arched portion of the plate N. The doors K at the front are also arched upward at the middle, the curvature corresponding substantially with that of the plate N.

Openings or panels I are formed 80 on the tops of these doors, and constitute a marked feature of the design. Above this plate are paneled faces O, bearing figures such as represented in the photograph. These paneled surfaces are surmounted by a projecting 85 cornice or molding, P. From this molding there rises what is commonly denominated the "magazine-section" Q, bearing on the front and on each of the two sides rectangular frames or panels R, and each of those at the end a tile 90 with an ornamental surface, the ornamentation consisting in the present instance of a Maltese cross arranged centrally thereon, and of vines and leaves grouped and entwined about said central figure. At the front the tile R is di-

COVER

vided into three panels, those at the rear end ornamented by a design representing a series of entwined vines and leaves, and that at the center ornamented by a Maltese cross with leaves grouped on either side.

Above the magazine-section there is a top plate S, the upper surfaces of which are beveled or inclined downward and upward, and ornamented by intaglio designs, such as shown. This top plate presents vertical or substantially vertical faces of considerable width, which are commonly burnished or polished to present bright smooth surfaces. The top plate is in turn surmounted by a covering-plate, T, located centrally thereon. This covering-plate has a molded outer edge, and is made of a size much less than that of the top plate.

Centrally on the covering-plate T there is an ornamental figure or statuette, U, representing a knight in armor mounted upon a charger, a lance being borne in one hand and a shield upon the opposite arm.

The rear side of the design is formed with an upright smoke-flue, V, of substantially rectangular form in cross-section. The rear panels may be made plain or with ornamentation.

At the top of the smoke-flue V there is a horizontal plate, W, ornamented by intaglio figures, as shown. The smoke-flue is also shown with a neck, X, extending rearward therefrom in a curved form, as shown. From this neck there extends a smoke-pipe or elbow, Y, curved in an upward direction and ornamented by figures in relief thereon, as shown.

Having thus described my invention, what I claim is—

A design for a stove, substantially such as herein described and shown.

NICHOLAS BRAYER.
